UNITED STATES PATENT OFFICE.

JOHAN HILMER DAHLGREN, OF STOCKHOLM, SWEDEN.

MACHINE FOR PRODUCING BLANKS FOR NAILS, HOOK-NAILS, HOOKS, OR THE LIKE.

1,171,506.

Specification of Letters Patent. Patented Feb. 15, 1916.

Application filed January 8, 1913. Serial No. 740,752.

To all whom it may concern:

Be it known that I, JOHAN HILMER DAHLGREN, a subject of the King of Sweden, residing at Stockholm, in the Kingdom of Sweden, have invented new and useful Improvements in Machines for Producing Blanks for Nails, Hook-Nails, Hooks, or the like, of which the following is a specification, reference being had to the drawings accompanying and forming a part hereof.

This invention relates to a machine for producing blanks for nails, hooks, nails, hooks or the like, and more specially, but not exclusively, to producing blanks, the cross section of which increases from one end of the blank to the other one, the material for the blanks being suitably introduced into the machine in the form of bars or wire and heated to a suitable degree. The further working of the blanks, as for instance the forming of heads, etc., will be effected afterward in a suitable machine adapted to that purpose.

In carrying the present method into effect the material is introduced into the machine in a well-known manner in the form of bars or wire and worked upon from different sides by blows from rotary rollers coöperating in pairs suitably arranged in groups and working the material alternately while the rollers are moving in circular paths around parallel or nearly parallel shafts arranged at opposite sides of the blank. The said method consists chiefly in that one or both of the shafts, around which the coöperating pairs of rollers are moving, move in directions toward and from the blank, simultaneously with the working thereupon by the rollers, thereby effecting a varying cross section of the blank during working. When the blank is thus finished it is separated from the bar by means of suitable tools.

In the machine for performing the present method the striking rollers are suitably arranged on holders attached to rotating shafts in such manner that two rollers are placed on a holder diametrically opposite to one another and at equal distances from the shaft, while the rollers coöperating with said rollers are arranged in a similar manner at the other side of the path of the material, so that the axes of the rollers of two coöperating pairs and the axes of the shafts of the corresponding holders lie in the same plane when a roller of each pair presses against

the blank. One or more of the rotating shafts carrying the holders are mounted on parts of the machine which are arranged to move in directions toward and from the material during working, thus effecting the above-named varying cross section of the blank. The tools separating the blanks from the material may be suitably placed on the holders of the rollers.

In the accompanying drawings a machine is shown adapted to carry the method into effect.

Figure 1 is an end view of the machine. Fig. 2 is a vertical section on the broken line A—B—C—D of Fig. 1. Fig. 3 is a vertical section on line E—F of Fig. 2. Fig. 4 shows two holders viewed from above and Fig. 5 same holders viewed from the side. Fig. 6 shows a finished blank. Fig. 7 is a plan view of the machine.

Referring to the drawings, 1 is the main shaft of the machine journaled in the frame 1' of the machine. By means of a worm gear 2 and a bevel gear 3 the main shaft 1 turns another shaft 4, to which two cam disks 5 and 6 are attached. By means of cams preferably interchangeably arranged upon the end face of the cam disk 5 a three armed lever 7, 8, is caused to perform an oscillatory movement, the reciprocating movement of the arms 8 being transmitted by a rod 9 to a frame 10 arranged to slide on the main shaft 1. A conical toothed wheel 11 movable along the main shaft 1, and splined thereto, and the shaft 25' of another conical toothed wheel 12 gearing with the wheel 11 are journaled in the frame 10, whereby the wheel 12 is caused to rotate. A third bevel wheel 13 is fastened to the shaft 1, and arranged to mesh with a fourth bevel wheel 14 fastened to the shaft 26' journaled in the frame 1'.

By means of lever 16 oscillating on a stationary pivot 15 and provided with a projection 17 or the like engaging the periphery of the cam disk 6, a rod 18, a bell crank lever 19, 20 and a rod 21, a crank 22 is caused to oscillate. The shaft 22' of the crank 22 is provided with another crank 27', the crank pin 28' of which is journaled in a block 23' sliding between guides 24' attached to a frame 23 which is movable on pivots 24 and by means of the said connections caused to oscillate on said pivots 24.

The tools effecting the working of the material consist of rollers 36 or the like rota-

tably mounted on pins. As shown in the drawings, said rollers are mounted in holders preferably in the form of rhombic disks with rounded corners.

5 The holders of the rollers are arranged in two groups, the holders 25 and 26 of one group rotating and working the material in the same horizontal plane, whereas the holders 27 and 28 of the other group rotate 10 and work the material in the same vertical plane. The holders 25 and 26 are mounted on rotatable shafts, the shaft 25' of the holder 25 being journaled in the frame 10 and at the same time forming the shaft of 15 the wheel 12, while the shaft 26' of the holder 26 forming the shaft of the wheel 14 is journaled in the machine frame. As shown in Fig. 2, the holders 25 and 26 preferably are formed in one piece with the 20 wheels 12 and 14 respectively. The shaft 29 of the holder 27 is journaled in the oscillating frame 23 and rotated by means of the toothed spur wheel 30 mounted on the main shaft 1 and the intermediate toothed wheels 25 31, 32 and 33, the last named 33 of which is attached to the shaft 29, while the wheel 32 is concentric with the pivots 24 of the frame 23. Thus it is evident that when the frames 10 and 23 are moving in the manner 30 above described, the shafts of the holders 25 and 27 will move in directions toward and from the shafts of the holders 26 and 28, said last named shafts remaining stationary. On account thereof, the rollers of 35 the holders 25 and 27, when lying in the same plane as the rollers of the holders 26 and 28 respectively, will assume positions nearer to or farther from the last named rollers, and consequently, the material inserted between coöperating rollers will obtain 40 a greater or smaller cross section according as the distance between the coöperating rollers increases or diminishes.

As stated above, the holders of the rollers 45 consist of disks preferably of about rhombic form with rounded corners. In notches in the ends of said disks are placed preferably cylindrical rollers 36, loosely mounted on pins 48 fastened in said holders or 50 disks. The holders of the rollers are so arranged relatively to the material introduced into the machine through a guide 37, that when a roller 36 in a holder, as for instance 55 27, strikes the material, one of the rollers in the holder 28 at the opposite side of the material simultaneously strikes said side of the material. The distances between the shafts of the holders and the material, and the size and speed of rotation of the holders 60 are so adapted, that coöperating rollers on

either side of the material always strike the same simultaneously. The two pairs of 65 holders 25, 26 and 27, 28 are so arranged, that they treat the material successively, that is to say, when the one pair, for instance the holders 27, 28 are in position for the rollers to treat the material (Fig. 2), the other pair of holders 25, 26 have swung a quarter of a full turn from their corresponding position, so that the plane through 70 the axes of the two rollers of the one holder 25 is parallel to the plane through the axes of the two rollers of the other holder 26. Thereby the result is attained, that the rollers of the different groups of holders can 75 work the material in the same cross-section thereof, without interfering with one another.

The finished blank is separated from the material introduced in the machine by 80 means of tools 39 and 40 attached to the holders 25 and 26 respectively. The guide 37 is mounted on a bar 44 connected to the frame 10, on account whereof, when the frame is moving on the shaft 1, the guide 85 37 and the material will follow the movements of the frame. When being operated upon, the material is fed forward through the guide 37 in a plane through all the rollers (Fig. 5), the distance between coöperating 90 rollers, when striking the material simultaneously, corresponding to the cross section of the blank. When the rollers have finished the working of the blank the above named movement of the guide 37 takes place 95 so that the blank will be moved out of the aforesaid plane to the right (Fig. 5) between the tools 39 and 40, and at the same time the rollers as well as the tools are moved close together to the position shown 100 in Fig. 5, whereby the finished blank in the form shown in Fig. 6 will be separated from the material.

I claim:

In a machine for producing blanks for 105 nails, hook nails, hooks or the like, the combination of rotatable rollers arranged at opposite sides of the material and adapted to move in circular paths, holders for said rollers, shafts for said holders, means for automatically moving certain of said shafts toward and away from the material during the operation, and means for separating the finished blank from the remainder of the material.

JOHAN HILMER DAHLGREN.
